UNITED STATES PATENT OFFICE.

CHARLES D. REYNOLDS, OF CRANSTON, RHODE ISLAND.

WINDING-MACHINE.

1,259,449.

Specification of Letters Patent. Patented Mar. 12, 1918.

Application filed October 5, 1916. Serial No. 123,861.

To all whom it may concern:

Be it known that I, CHARLES D. REYNOLDS, a citizen of the United States, residing at Cranston, in the county of Providence, State of Rhode Island, have invented certain new and useful Improvements in Winding-Machines, of which the following is a specification.

My invention relates to winding machines and consists of improvements in the construction and method of operation of the same. The objects of my improvement are to simplify the mechanism of the machine by reducing the number of its parts; to reduce the weight of the parts to provide for high-speed operation, and also for the sake of economy in cost of manufacture; to compact the mechanism within a minimum compass to save floor space, and to otherwise render the machine more efficient in operation and more durable in use as more fully pointed out hereinafter.

The manner and means for carrying out the improvement are fully described in the following specification, illustrated by the accompanying drawings, in which like reference characters designate like parts. In the drawings:

Figure 1 is a side elevation of one of the component units or heads of the machine, illustrating the essential elements of the winding-mechanism and the manner in which it is mounted on the longitudinal frame or bed shown in section;

Fig. 2, an end elevation of the winding head or unit shown without the bed;

Fig. 3, an enlarged view of a portion of the winding unit showing the detail of the stopping-mechanism for the winding-spindle;

Fig. 4, an end view of the mechanism shown in Fig. 3, illustrating the tension and end-stop devices for the yarn; and

Fig. 5, an enlarged, detail view of the traverse-mechanism of the machine.

Referring first to Fig. 1, 2 designates the troughlike frame or bed of the machine which is supported in horizontal position on suitable legs or standards, not here shown, and on which is mounted any desired number of winding units or heads. The bed 2 is constructed with overhanging side-flanges 3 on which the framework of the heads rests, and as here shown its bottom is left open to receive a dished drip-pan 4 supported on inwardly projecting

ledges 5. Set into the bed 2 are a series of casings 6 spaced at intervals along the machine to inclose the traverse-mechanisms for the several winding units or heads. As 60 all of the heads are of the same construction and arrangement, only one is herein shown and described, and it will be understood that as many units as required may be applied to the bed 2 in accordance with 65 the length to which it extends. As shown in Figs. 1 and 2, the casings 6 are constructed in the form of narrow, semi-cylindrical boxes having relatively thin side-walls 7 and projecting flanges 8 at the top 70 overlapping the horizontal side-flanges 3 on the bed 2, to which they are secured by bolts 9. Journaled in alining bearings 10 at the ends of the bed 2, see Fig. 2, and extending through openings in the sides 7 of 75 the casings 6 is a horizontal cam-shaft 11 which reaches the whole length of the machine. The shaft 11 is driven from a belt or other suitable means at one end, the driving connections not being here shown or 80 described as they may be of any well known arrangement. The shaft 11 carries a plurality of heart-shaped traverse-cams 12, which are keyed thereto at 13, see Fig. 1, to adapt them to revolve in the casings 6, 85 the latter serving as oil-reservoirs therefor.

The opposite side walls 7 of the casings 6 are flanged at the top at 14 and milled off along their upper edges to provide the parallel, finished faces 15. Extending along the flanges 14 are cleat-like strips 16 bolted to lugs 17 on the casing 6 by means of the screws 18, see Figs. 1 and 2. The cleats 16 overhang the finished faces 15 of the casing 6 with a space therebetween to provide the opposite slots 19 in which a reciprocating crosshead or traverse-slide 20 is adapted to slide. If preferred, however, the slots at the top of the casing 6 could be cut 100 in its sides without requiring the upper cleats 16, the arrangement shown being designed more particularly for convenience in constructing and assembling the parts. As illustrated in Figs. 1, 2 and 5, the slide or 105 crosshead 20 is preferably constructed of sheet-metal bent up in substantially cradle-shape to render it staunch and strong while reducing its weight to adapt it for high-speed reciprocation. Its opposite, longitudinal sides 21 are joined at the ends by horizontal cross-strips 22, see Figs. 2 and 5, from

which depend ears 23. Extending between the ears 23 are lateral bearing-pins 24 carrying rolls 25 which are adapted to ride on the opposite sides of the peripheral face of the cam 12. Projecting from the sides 21 of the slide 20 are horizontal ears or runners 26 fitted to the slots 19 in the casing 6 to adapt the crosshead to slide therein when the cam 12 is rotated with the rolls 25 following its eccentric face. The reciprocating slide 20 is adapted for connection with a pair of pivoted traverse-levers 27, only one being here shown, to oscillate the latter to traverse the thread-guides of the machine 15 in the manner as next described.

Each cam 12 is arranged to operate the traverse-levers for two adjacent winding-heads or units, but as the connections for both levers are the same, only one is herein shown and described. Referring particularly to Figs. 1 and 2, the cam-casing 6 has attached to its under side a bearing-member 28 secured thereto by the screws 29 or in any other convenient manner. Extending upwardly from the member 28 are two elbowed arms 30 formed at the top with bearings 31 for the pivot-shafts 32 of the traverse-levers, only one of which is shown in the drawings. The inner end of the pivot-shaft 32 abuts the 30 end of a lug 33 on the side of the casing 6 to locate it in position in its bearing 31 and a set-screw 34 secures it in place. The traverse-lever 27 comprises two telescopic parts, one slidable longitudinally of the other to 35 provide for extending the length of the lever for a purpose as later described. The heel or pivot portion of the lever 27 is of fork-like construction comprising two arms 35, 36 mounted on the projecting ends of the shaft 40 32, straddling the bearing 31. Slidably fitted to the arm 36 is the longer, extensible portion 37 of the lever 27 which is preferably constructed of sheet-metal for the purpose of reducing its weight, see Fig. 2. At 45 its lower end the extension 37 is formed with wings 38 bent to overlap the sides of the arm 36 to adapt it to slide longitudinally thereof and its main portion is slotted at 39 to provide a clearance for the pivot-shaft 32, see 50 Fig. 5. Bent at right-angles to the vertical portion of the lever-extension 37 is a finger 40 projecting across the top of the arm 36 to adapt it to limit the downward movement of the extension on the arm, see Fig. 2. A 55 coiled spring 41 is hooked into the end of the finger 40 and anchored at its lower end to a hook 42 on the arm 36, thereby tending to maintain the extension 37 in its retracted position while allowing it to slide vertically 60 upward in the manner and for the purpose as later explained. Referring to Fig. 5, the extension 37 of the lever 27 takes the form of a sickle-shaped loop at 43 to adapt its side to clear the cam-shaft 11 as it oscillates 65 back and forth across the axis thereof. Be-

yond the loop-portion 43 the extension 37 is formed with an upright arm 44 in line with its pivot-arm 36. Secured to the side of the arm 44, or formed from a cut-out portion of the metal thereof, if preferred, 70 is a finger 45 which serves as an outer support for a pin 46, see Fig. 2, driven through the arm. Journaled on the pin 46 is a roll 47 which is adapted to ride on the upper edge of the side 21 of the crosshead 20 as 75 shown in Fig. 5; or to engage a slot 48 therein as illustrated in Fig. 1. The slot 48 is formed with a marginal flange 49 to provide a more extended bearing surface for the roll 47, thereby increasing the durability of the 80 engaging parts. It will be understood that the slide or crosshead 20 is reciprocated continuously from the cam 12 and when the roll 47 is engaged with its slot 48 the traverse-lever 27 will be oscillated thereby. When, 85 however, it is desired to arrest the operation of the thread-guide, which is connected to the lever 27 as later described, the extension 37 is slid upwardly on its pivot-arm 36 to raise the roll 47 out of the slot 48 and the crosshead 20 will then slide beneath the roll 47 without imparting movement to the traverse-lever. The manner and means for coupling and uncoupling the lever from the crosshead 90 will be later described in detail in connection with the stopping-mechanism of the machine.

Mounted on the bed 2 at intervals along its length are a plurality of upright standards or brackets 50 which serve as supports 100 for the fixed winding-spindles of the machine. The brackets 50 are arranged in pairs, one on either side of each cam-casing 6, and are provided with legs 51, 52 straddling the central cam-shaft 11, see Fig. 3, 105 with their feet bolted to the side-flanges 8 of the bed 2. Adjacent the top of each bracket 50 is a bearing 53 in which is fixedly secured the dead-spindle or shaft 54 which carries the rotatable winding-mandrel or 110 cone-holder 55. All of the several brackets 50 are of the same construction and therefore only one is shown in the drawings, but it is to be noted that they are arranged along the bed 2 in right and left positions in relation thereto, so that the spindles 54 project alternately on opposite sides of the machine. Through this system of arranging the spindles the several units or heads of the machine are grouped in more compact formation to economize floor space, while allowing the winding-mechanisms to be operated from both sides of the machine.

Rotatably mounted on each winding-spindle 54 is a belt-pulley 56 having its hub 125 abutting the end of the bearing 53, see Fig. 3. The series of pulleys 56 on the several spindles 54 are arranged in alinement along the length of the machine and are driven from an endless belt, not here shown, pass- 130

ing over them and held in contact therewith by suitable idler-pulleys. The belt is driven from a main driving-pulley at the end of the machine, which, in turn, is connected 5 with the cam-shaft 11 through the means of gears, belts or the equivalent. Usually a "gainer" or speed-changing mechanism is employed in connection with the driving-elements to provide for adjustment between 10 the speed of the pulleys which drive the cop-holders and the speed of the shaft 11 which operates the several traverse-mechanisms. These driving and change-speed connections are not herein shown or described in detail, 15 however, as they may be of any well known arrangement as usually applied to machines of the present type.

The driving-pulleys 56 are connected to 20 rotate the cop-holders or winding-mandrels 55 as next described: As illustrated in Figs. 1 and 3 the cop-holder 55 is constructed in the form of a tapered mandrel adapted to fit 25 the interior of the conical paper-tube or shell on which the cone-package is to be wound. In some cases, however, where the machine is to be employed for winding cylindrical packages, or "cheeses", as they are sometimes termed, the cone mandrel is removed and a cylindrical tube-holder substituted. In either case the driving-connections are the same, and consist essentially 30 of a clutch-member 57 rotatable with the cop-holder 55 and slideable on the spindle 54 to adapt its tapered face 58 to engage the correspondingly formed clutch-face 59 of 35 the pulley 56. The clutch-member 57 also performs a further function, that of operating the expanding dogs or grippers which secure the cop-tube on the holder 55, but as 40 this portion of the mechanism is shown and described in my companion application for patent, Serial No. 109,878, filed July 18, 1916, it will not be herein explained. Suffice it 45 to state, for the present, that the clutch 57 is operated by a spring, not here shown, to normally maintain it in engagement with the pulley 56 and is adapted to be disengaged therefrom by means of a lever 60. The method of operation of the lever 60 50 will be explained in connection with the automatic stopping-mechanism of the machine to be later described.

The traversing thread-guide 61, which is reciprocated longitudinally of the winding- 55 mandrel or cone-holder 55 to lay the coils of yarn thereon, is mounted to slide on a traverse-frame 62 shown in Figs. 1 and 2. Referring first to Fig. 3, a lug 63 projects from the side of the standard or bracket 50 and in this is fixedly secured a vertical, threaded stud 64. Mounted on the stud 64 and held in place by a nut 65 is a hub 66, shown in Fig. 2, from which extends a horizontal arm 67, see also Fig. 1. Formed in 60 the front face of the arm 67 is a semi-cir-

cular groove 68 which serves as the track or guideway for the sliding thread-guide 61. The hub 66 may be turned about the axis of the stud 64 to adjust the track or arm 67 in relation to the winding-mandrel in accordance with the shape thereof. That is to say, when a tapered mandrel 55 is employed, as shown in Figs. 1 and 2, the arm 67 is set at an angle to its axis so that the guide 61 will travel parallel with the inclined surface of the mandrel. When a straight mandrel is used for winding "tubes", or "parallel" packages as they are sometimes called, the track or arm 67 is set parallel with the axis of the spindle 54. In either case the 70 arm or track 67 is secured in its adjusted position by means of the set-screws 69 in the hub 66. Fig. 4 shows the arm 67 set parallel with the axis of the spindle 54, or at right-angles to the side of the machine and 75 gives the best view of the construction and arrangement of the traverse-frame.

Referring to Fig. 1, the traverse thread-guide 61 is preferably constructed of sheet-metal, to render it light in weight, and is 80 formed at its base with an offset portion or extended runner 70. The runner 70 is bent to an arcuate form in cross-section, as shown in Fig. 4, to adapt it to fit the semi-circular groove 68 in the traverse-frame track or arm 85 67. A cleat 71, Figs. 1 and 4, extending along the arm 67 and secured thereto by the screws 72 is formed at its top with a semi-circular bead 73 fitted to the groove 68 in male-and-female fashion. A relatively narrow space is left between the face of the bead 73 and the side of the groove 68, forming a slot 74 in which the shoe 70 of the guide 61 slides. On the back of the runner 70 of the guide 61 are two fingers 75, 75 100 bent out to form a cup-like socket for the spherical head 76 of a rod 77. The opposite end of the rod 77 also carries a ball-like head 78 fitted to a socketed bearing 79 at the end of the traverse-lever arm 44, whereby 105 the guide 61 is connected to be reciprocated therefrom. The upper portion of the guide 61 is of skeleton construction, as shown in Fig. 1, comprising the converging sides or branches 80, 80 joined together at the top 110 and having an offset blade 81, formed on its under side with a thread-notch 82. Extending across the thread-notch 82 is a wire finger 81^a over which the yarn draws as it leads to the notch. The guide 61 sets in a 115 substantially vertical position as shown in Fig. 4, but is adapted to pivot in the guiding-slot 74 of the arm 67 to adapt its guiding-blade 81 to be brought into contact with the surface on which the yarn is laid. As 120 the yarn builds up on its tube or holder the guide 61 swings outwardly away from the axis of the winding-mandrel 55 with its position controlled by a pivoted traverse-frame back 83. This latter element con- 125 130

sists of a substantially flat plate or bearing-member 84 supported by two arms 85, 85, see Figs. 1 and 4, which are pivoted on a rod 86 in lugs 87 on the under side of the 5 arm 67. A coiled spring 88 surrounds the rod 86 between the central lug 87 on the arm 67 and the inner bearing 89 of the back 83, tending to force the whole frame side- 10 wise on the rod 85 in the direction indicated by the arrow *b*, Fig. 1. On the side of the plate 84 of the traverse-frame back 83 is a projection or lug 90 arranged with its end engaging the finished face of a curved arm or sector 91. The sector 91 is 15 arranged concentric with the axis on which the traverse-frame back 83 swings and is fixedly supported with respect to the traverse-frame by an arm 92 reaching up from the track 67, see Fig. 2. Through this ar- 20 rangement the pressure of the spring 88 tending to slide the traverse-frame back 83 on its rod 86 maintains the lug 90 bearing against the sector 91 with sufficient frictional resistance to prevent undue movement 25 of the thread-guide 61 as the latter is forced away from the mandrel 55. That is to say, the friction between the lug 90 and sector 91 provides a dogging action to prevent the traverse-frame back 83 from forcing the 30 guide 61 toward the axis of the winding-spindle after it has once been carried away therefrom. As shown in Fig. 2, the traverse-frame back 83 carries a weighted arm 93 to counterbalance its weight and that of 35 the parts carried thereby. The weights 94 are applied to the arm 93 by slipping them onto a rod 95 projecting rearwardly from its side, and in this way any desired amount of pressure can be applied to the thread- 40 guide to resist its outward movement as the yarn-package builds up on the winding-mandrel 55. The tension of the spring 88, however, is sufficient to maintain the lug 90 on the traverse-frame back 83 bearing 45 against the dog-sector 91 with enough friction to resist the maximum amount of pressure applied to the frame.

It is well known by those skilled in the winding art that a yarn-package or cone can 50 be built more compactly and uniformly if considerable pressure is applied to the guide at the beginning of the winding, but it is also a fact that the pressure must be reduced as the winding nears completion or 55 the ends of the package will become bulged and malformed. In view of this it is a common practice to provide the winding-guide with a differential pressure-device so-called, and in the present machine this is arranged 60 as next described: Extending through bearings 96 at the top of the several brackets or uprights 50, see Figs. 1 and 2, are two parallel rods 97, 97 which reach the whole length of the machine and serve as a means 65 for supporting brackets for the idler-pul-

leys and various other attachments to the winding-mechanism proper. A pair of such brackets 98, 98 are clamped to the rods 97 by the bolt 99, see Fig. 1, and at one side thereof is a bearing for a pin 100. Pivoted 70 on the pin 100 is an arm 101 carrying a rod 102 at its end on which are mounted a plurality of weights 103 held in place by a collar 104. Pivotedly connected to the rearward end of the rod 102 is a link 105, see 75 Fig. 1, having its lower end hinged on a pin 106 projecting from the side of the swinging traverse-frame back 83. As shown in Fig. 2, the link 105 sets at an angle to the weight-arm 101 when the thread-guide 80 61 is in a position adjacent or close to the winding-mandrel 55, but as the guide swings outwardly the link will be carried toward the vertical, thereby rocking the arm 101 to raise the weights 103. The inclination of 85 the link 105 varies with the movement of the guide as the latter recedes from the winding-mandrel during the growth in diameter of the package and in this way the link acts as a sort of toggle connection be- 90 tween the traverse-frame and the pressure-weights 103. Through this means the effect of the weights 103 on the frame is gradually reduced from start to finish of the winding until eventually when the link 105 95 stands in a vertical position, their pressure on the frame will be practically *nil*.

The automatic stopping-mechanism of the machine is illustrated particularly in Figs. 3, 4 and 5 and will be next described: Referring first to Fig. 3, the clutch-lever 60, previously mentioned, is pivoted on a pin 107 held in an extension 108 of the upright or bracket 50. A second pin 109 supported on the bracket 50 at right-angles to the pin 105 107 serves as a pivot for a lever 110, the hub of which is shown by dotted lines in Fig. 3. The lever 60 has a horn-shaped arm 111 reaching out to the right from its hub with its end adapted to rest on a projection 110 or lug 112 on the hub of the lever 110. Referring now to Fig. 4, the main arm 113 of the lever 110 is offset at its lower end and formed with a square shoulder 114 adapted to engage with a corresponding shoulder 115 115 on a detent-lever 116. The detent-lever 116 is of bifurcated form having two legs 117, 117 pivoted on a pin 118, see Fig. 3, held in the bracket 50, below and parallel with the pin 109. A relatively light, coiled spring 120 119 is stretched between the detent-lever 116 and the curved arm 111 of the lever 60, tending to maintain said arm bearing on the lug 112 of the lever 110, and also to rock the lever 116 to cause it to engage the shoulder 115 with the shoulder 114 on the lever 110. A stronger spring 120, anchored to a lug 121 projecting from the upright 50, has its opposite end hooked around the end of the arm 113 of the lever 110. The spring 130

120 acts to rock the lever 110 in the direction indicated by the arrow *c*, Fig. 4, when the detent-shoulders 114, 115 are released, thereby causing its lug 112 to raise the arm 111 of the lever 60. This action causes the upright arm of the lever 60 to be rocked to the left, as viewed in Fig. 3, and as its end engages the side of a flange 122 on the clutch 57 the latter will be slid on the spindle 54 5 to disengage it from the driving-pulley 56. The lever 60 is controlled manually in starting the machine by means of a hand-lever 123 supported on the same pivot-pin 107. The lever 123 is formed with a curved handle 124 and two opposite arms 125, 126 10 adapted to engage the sides of the lever 60 with a slight clearance therebetween, see Fig. 3. The hand-lever 123 is also provided with a curved arm 127 adapted to engage the outer end of the arm 113 of the lever 110 to rock the latter downward to engage its detent-shoulder 114 with the shoulder 115 on the detent-lever 116, the method of 15 operation of these parts being more fully explained hereinafter. At the extreme outer end of the arm 113 of the lever 110 is a cross-piece 128 of bow-like form having a slight depression 129 on its top, see Fig. 3. The cross-piece or bridge 128 acts as the means for lifting the traverse-lever extension 37 to raise its roll 47 out of the slot 48 in the traverse-slide or crosshead 20. Referring to Fig. 5, the lever-extension arm 44 is pierced with an opening 130 at its top and 20 the portion of metal cut away is bent at right-angles to form a projecting finger 131. The finger 131 is preferably rounded on its under side to adapt it to slide across the crowned top of the bridge-piece 128 and to 25 set in the depression or slot 129 at its center. Referring again to Figs. 3 and 4, the legs 117 of the detent-lever 116 reach forward in the extensions 132, 132 and extending between their ends is a cross-pin 133. Pivotally mounted on the pin 133 is a vertical plate 134, widened at its bottom and formed with two prongs 135, 135, see Fig. 3. The prongs 135 are adapted to engage with the fluted periphery of a toothed-wheel or 30 ratchet 136 mounted fast on the cam-shaft 11 and rotated continuously therewith. Normally the plate 134 hangs pendulous at one side of the wheel 136 with its prongs 135 clear therefrom, see Fig. 4. By rocking the plate 134 into engagement with the wheel 35 the teeth on the latter will act on the prongs 135 to raise the plate bodily, thereby rocking the detent-lever 116 to free its shoulder 115 from the shoulder 114 on the lever 110. The plate 134 is operated to release the detents by means of an end-stop-lever 138, preferably constructed of wire to render it light in weight and sensitive in operation. As 40 shown in Figs. 3 and 4 the wire of the lever 138 is coiled at 139 and 140 to encircle the 45 ends of a pin 141 which serves as its pivot. The pin 141 is driven through lugs 142 extending from a bracket or arm 143 which is fixedly mounted on the pivot-pin 118 of the lever 116 and reaches down to one side of the plate 134. One arm 144 of the lever 138 reaches up and across the front of the plate 134 and the other 145 extends horizontally outward to coöperate with the tension-device which regulates the delivery of the 50 yarn to the thread-guide 61.

Any suitable arrangement of tension-means may be employed in connection with the winding-mechanism and I have illustrated a preferred form in Fig. 4. As here shown the tension-members are mounted on a vertical arm or bracket 150 supported at any convenient position on the frame or bed 2. Projecting horizontally from the top of the arm 150 is a lug 151 carrying a pin or 55 screw 152 on which is pivoted one of the tension-members 153. This latter consists of a flat plate or strip of sheet-metal bent in a curve slightly eccentric to its pivot and providing a rounded face 154 across which the 60 thread or yarn *y* draws. The pressure of the yarn maintains the tension-member or plate 153 normally in the position shown in Fig. 4 with its end 155 bearing against a fixed horn 156 on the top of the arm 150. 65 A tail-piece 157 on the member 153 reaches up at the rear of the pivot 152 and is adapted to strike against the under side of the arm 145 of the end-stop-lever 138. Below the tension-member 153 is a second, fixed member 158 comprising a curved plate 159 secured to a lug 160 on the arm 150. At the bottom of the arm 150 is a third lug 161 to which is pivoted a swinging lever 162. The lever 162 carries a projection 163 having a 70 concaved, curved face over which the yarn *y* drawn as it leads across the members 153 and 159. At the lower end of the lever 162 is a pigtail 164 through which the yarn leads to direct it to the tension-member 159. The 75 position of the lever 162 may be adjusted by suitable means, not here shown, to displace its projection 163 with respect to the other tension-members 153 and 158, whereby a greater or less bend is made in the yarn 80 drawing through the tension-device, and through this arrangement the amount of tension applied to the yarn is regulated in the usual manner. The method of operation of the complete machine is as follows:

To prepare the machine for winding the cone or package, a paper cop-tube or shell is first placed on the mandrel or holder 55 and secured thereto in any suitable manner as generally employed. The thread or yarn *y*, 85 see Fig. 4, is then drawn up from its source of supply, usually placed below the machine, but not here shown, and then carried through the tension-device on the arm 150. The yarn leads through the pigtail 164, up 90

over the fixed tension-member 159, thence around the member 163 on the lever 162, and back around the other fixed member 153 to impart to it a sinuous course whereby its draft will be resisted in the well known manner as usually employed. From the upper tension-member 153 the yarn y is led up across the top of the traverse-frame back 83, thence over the wire-guide 81^a on the 10 guide 61, and through the notch 82 in the blade 81. The end of the yarn is then secured to the tube on the mandrel 55 by winding it therearound, or in any other suitable manner and the machine is ready to operate 15 to wind the package.

With the machine at rest the lever 60 bears against the flange 122 on the clutch-member 57 to hold the latter free from engagement with the driving-pulley 56 so that the mandrel 55 will be held from rotation. At the same time, the bridge-piece 128 on the lever 110 holds the traverse-lever extension 37 raised with its roll 47 clear of the slot 48 in the traverse-slide 20, as shown in Fig. 5, 20 so that the latter reciprocates without imparting motion to the lever and its connected thread-guide 61. To start the operation of the winding-mandrel and thread-guide the handle 124 is raised to carry the arm 125 25 against the lever 60, thereby rocking the latter to the right as viewed in Fig. 3. The upright arm of the lever 60 is thus carried away from the side of the flange 122 on the clutch 57 to allow the latter to engage with 30 the driving-pulley 56. The pulley 56 is driven continuously, as before explained, and through its engagement with the clutch 57 rotates the connected winding-mandrel or cop-holder 55 in the direction indicated 35 by the arrow d , Fig. 4. The yarn y is thus drawn up through the tension-device while the thread-guide 61 is traversed along the cone-holder 55 as next explained to deposit the coils of winding thereon.

40 As the hand-lever 123 is raised to rock the clutch-lever 60, its curved arm 127 is brought down against the end of the arm 113 of the lever 110, see Figs. 3 and 4. The lever 110 is thereby rocked downwardly to engage its 45 detent-shoulder 114 with the shoulder 115 on the detent-lever 116, the latter being allowed to tilt slightly by the stretching of its spring 119. As the arm 113 swings downwardly to lock the detents the cross-bar or bridge 128 at its end drops to allow the traverse-lever extension 37 to be telescoped on its arm 36 under the action of its 50 spring 41, see Fig. 5. The roll 47 on the extension 37 thereby drops down into contact with the upper edge of the traverse-slide 20 which rides beneath it. As before stated, the slide 20 is reciprocated continuously from the cam 12 engaging its rollers 55, and as the slot 48 comes into alinement 60 with the roll 47 on the lever-arm 44, the

spring 41 will draw the extension 37 down to seat the roll in the slot as illustrated in Fig. 1. This coupling of the traverse-lever with the slide 20 takes place at the first stroke of the latter after the release of the extension 37, or practically at the instant of starting the winding-mandrel. The traverse-lever 37—36 is then oscillated by and with the slide 20 to rock it on its pivot 32. As the traverse-lever rocks back and forth 75 across the axis of the cam 12, it acts through the link 77 to reciprocate the thread-guide 61 longitudinally of its slot 74 in the traverse-frame arm 67. In this manner the guide 61 is traversed along the winding- 80 mandrel 55 to lay the yarn in helical coils which build up in overlying layers to form the cop or package. In winding conical packages the thread-guide track or slotted arm 67 is set at an angle to the axis of the 85 cone-holder 55 to allow the guide to travel in the path parallel with the surface on which the winding is being deposited, as shown in Fig. 2. The adjustment of the track 67 is made by releasing the nut 65 and 90 turning the hub or bearing 66 on the stud 64, the set-screws 69 being employed to lock the arm 67 in position as before explained. For winding cylindrical packages the arm 67 is set parallel with the axis of the winding-spindle 54, see Fig. 4, and the conical mandrel 55 is displaced by a cylindrical tube-holder, not herein shown. 95

As the yarn builds up on the winding-mandrel and the package increases in diameter, as indicated by the dash-lines in Fig. 4, the thread-guide 61 is forced outwardly away from the axis of the cop against the pressure exerted upon it by the weighted traverse-frame back 83. Meanwhile the 100 spring 88, see Fig. 1, acts on the traverse-frame back to cause its lug 90 to bear against the dog-sector 91, thereby creating a slight friction therebetween so that the plate 84 is steadied in its movement and 105 prevented from vibrating or jumping under the influence of inequalities in the winding. It will be understood, of course, that the traverse-lever 37—36 oscillates in a fixed plane, but the guide 61 is allowed to swing 110 back and forth relatively to this plane, or to travel in a path inclined thereto, in the case of cone winding, due to the universal or ball-and-socket connections of the link 77 with the guide and lever. As the guide 115 recedes from the winding-mandrel with the growth of the package the traverse-frame back 83 acts through the link 105, see Fig. 2, to raise the weighted lever 101, and through the toggle-action of the link the 120 pressure of the plate 84 against the guide is gradually reduced in the manner and for the purpose as before explained. 125

The method of operation of the automatic stopping-mechanism of the machine is as 130

follows: When the yarn *y* breaks, or its supply becomes exhausted, the release of its pressure against the pivoted tension-member 153, see Fig. 4, will allow the latter 5 to drop down through the action of gravity. In this case its tail-piece 157 will strike against the under side of the arm 145 of the end-stop-lever 138, causing its extension 144 to swing the hanging plate 134 into 10 position above the ratchet 136, see Fig. 3. The teeth on the ratchet 136 will then act on the prongs 135 to raise the plate bodily to tilt the detent-lever 116 upwardly. This 15 action unlocks the detent-shoulders 114, 115 to free the lever 110 which is caused to tilt upwardly under the action of its spring 120, see Figs. 3 and 4. As the lever 110 is rocked by its spring 120 its lug 112 lifts the arm 111 of the lever 60 causing the 20 right arm of the latter to swing to the left, as viewed in Fig. 3. This causes the clutch 57 to be withdrawn from the driving-pulley 56 and the winding-mandrel 55 will therefore cease to be rotated thereby. As the 25 arm 113 of the lever 110 swings upwardly its bridge-piece 128 is raised to bring it into the path of the finger 131 on the traverse-lever extension 37. The finger 131 will therefore be caused to ride up over the 30 arched incline of the bridge 128 during the next reciprocation of the traverse-lever in either direction until it finally seats in the depression 129. The roll 47 on the extension 37 is thus drawn up out of the slot 48 in the traverse-slide 20, as shown in Fig. 5, and the latter will reciprocate without imparting movement to the lever as before explained. The traverse-lever 27 is thus held 35 inoperative to arrest the traverse of the 40 thread-guide 61 and the engagement of the finger 131 with the notch 139 acts as a detent to prevent accidental or unwarranted movement of the lever which might cause it to be reengaged with the slide 20.

45 It will be observed that my improvements result in simplifying the construction of the mechanism of the machine and reducing the number and weight of the parts, whereby they are better adapted for high speed operation, most of the operating elements being constructed of sheet-metal provide for the minimum of weight without sacrificing the necessary strength and stiffness, while at the same time securing economy in their 50 cost of manufacture. The several units of the machine are so grouped along the bed or frame as to economize space, whereby a greater number of spindles may be placed in a given area than has heretofore been 55 practicable. Each single traverse-cam and slide serves to operate the guides of two units so that only half the number of traverse-motions usually employed are required for any given number of spindles, 60 while at the same time the starting and

stopping of each guide is controlled individually and independently in accordance with the preferred practice. Only a single gainer-mechanism is required for all of the heads, and therefore the driving-connections 65 are considerably simplified and improved. It is also to be noted that the several heads are independently adaptable for winding either conical or cylindrical packages with only slight adjustment of the mechanism. 70 No new parts are required for such adjustment except as regards the cop-holder or winding-mandrel and this can be easily and quickly changed without substituting a different style of traverse-mechanism. The 75 machine is also capable of being operated with less power than usually required where separate traverse-motions are employed for each spindle, and in other respects the going parts are much lighter and easier running. 80 A particular feature of improvement to be observed is the reduction in the number of spindle and cam-shaft-bearings required and the elimination of other wearing parts. 85

Various modifications might be made in 90 the form and arrangement of the elements of the mechanism of the machine without departing from the spirit or scope of the invention; therefore, without limiting myself to the exact embodiment shown and described, what I claim is:—

1. In a winding machine, the combination with a series of winding-mandrels arranged in opposed relation with their axes in the same horizontal plane, of individual 100 driving-pulleys for the several mandrels arranged in horizontal alinement to be driven from a single belt, clutches connecting said pulleys to drive the mandrels, means to independently connect and disconnect the clutches from the driving-pulleys, a thread-guide for each mandrel, an oscillating lever connected to reciprocate each thread-guide, a traverse-slide adapted to be reciprocated in a horizontal path between 105 each pair of levers, a cam to reciprocate the slide, and means to connect each pair of levers to the opposite sides of their respective slide to cause them to be reciprocated therefrom to traverse their thread-guides. 110

2. In a winding machine, the combination with a series of winding-mandrels arranged opposite each other in staggered relation with their axes in a horizontal plane, of a traverse-cam for each pair of 115 associated mandrels, said cam rotatable on an axis at right-angles to the axes of the mandrels, a traverse-slide connected to be reciprocated from each cam, a pivoted lever on each side of the traverse-slide, means to 120 independently connect said levers with their respective slide and thread-guides connected to be reciprocated from the levers to traverse opposite the winding-mandrels. 125

3. In a winding machine, the combina- 130

- tion with a frame having bearings for a horizontal cam-shaft, of standards on said frame, a series of winding-mandrels rotatable on bearings on the standards with 5 their axes arranged at right-angles to the cam-shaft, a plurality of cams on the cam-shaft, slides connected to be reciprocated from said cams, thread-guides adapted to be traversed in relation to the winding- 10 mandrels, means connecting each pair of opposite thread-guides with the same slide to adapt them to be reciprocated therefrom, and means for independently uncoupling each connecting-means from the slide.
- 15 4. In a winding machine, the combination with a horizontal frame, of a series of standards supported on said frame, winding-mandrels rotatably mounted on said standards in parallel relation on opposite sides 20 of the frame, a horizontal cam-shaft journaled on the frame with its axis at right-angles to the axes of the winding-mandrels, a series of cams on the cam-shaft equal in number to half the number of winding- 25 mandrels, a slide connected to be reciprocated from each cam, thread-guides adapted to be traversed in relation to the winding-mandrels, and means connecting each pair of adjacent thread-guides on the opposite 30 sides of the machine to be reciprocated from the same slide.
- 35 5. In a winding machine, the combination with a series of fixedly supported dead-spindles, of driving-pulleys rotatable on said spindles, cop-holders rotatable on the spindles, clutches for connecting the cop-holders with the driving-pulleys, a traverse-cam between each alternate pair of spindles, a single traverse-means reciprocated from 40 each cam, a pair of thread-guides connected to each traverse-means to be reciprocated opposite the cop-holders, and means for independently operating the clutch for each cop-holder and for concurrently disconnecting the associated thread-guide from its 45 traverse-means.
- 50 6. In a winding machine, the combination with a series of non-rotatable spindles, of driving-pulleys rotatable on the spindles, cop-holders rotatable on the spindles, clutches for connecting the cop-holders with the driving-pulleys, a single reciprocating traverse-means for each alternate pair of spindles, a pair of thread-guides connected 55 to each traverse-means to be reciprocated opposite adjacent cop-holders, manually-operable means for shifting the clutches to connect each cop-holder with its driving-pulley and for concurrently connecting each guide 60 with its traverse-means, and automatically-operated means for shifting the clutches to independently disconnect the cop-holders from the driving-pulleys and to simultaneously uncouple their associated guides from 65 the traverse-means.

7. In a winding machine, the combination with a pair of rotatable winding-mandrels, of means to rotate said mandrels, a reciprocating crosshead, means to reciprocate the crosshead, a pair of thread-guides both connected with the single crosshead to be reciprocated therefrom, and means to arrest the rotation of each winding-mandrel individually and to concurrently disconnect its associated thread-guide from the crosshead 75 independently of the other guide.

8. In a winding machine, the combination with a pair of horizontally-arranged winding-mandrels extending in opposite directions, of separate means for driving each 80 mandrel, a thread-guide for each mandrel, a single reciprocating-means connected to both guides to traverse the latter in opposed relation to their respective mandrels, starting- and stopping-means for controlling 85 the rotation of the mandrels individually, and means operating in conjunction therewith to individually and independently connect and disconnect the related thread-guide of each mandrel from the single reciprocating-means.

9. In a winding machine, the combination with a pair of rotating winding-mandrels on which the yarn is wound, of a traverse-cam, a crosshead reciprocated from said 95 cam, a pair of thread-guides adapted to be traversed opposite the mandrels, means for coupling both of said guides to the single crosshead to be reciprocated therefrom, and means for independently disconnecting the 100 guides therefrom to individually arrest their operation.

10. In a winding machine, the combination with a pair of rotating winding-mandrels, of a continuously rotated heart-shaped 105 cam arranged below said winding-spindles with its axis at right-angles to the axes thereof, a track above the cam, a crosshead adapted to slide on the track at right-angles to the axis of the cam, means on the cross-head engaging the periphery of the cam to adapt it to be reciprocated therefrom, a pair of thread-guides adapted to be traversed in relation to the opposite winding-mandrels, independent means for connecting 110 each guide with the crosshead to adapt it to be reciprocated therefrom, and stopping-mechanism for individually uncoupling the connecting-means to arrest the operation of either of the guides.

11. In a winding machine, the combination with the rotatable winding-mandrel, of a continuously-rotated disk-like cam, a crosshead straddling the sides of the cam to adapt it to slide across the axis thereof, means on the crosshead engaging the periphery of the cam to adapt it to be reciprocated therefrom, a thread-guide arranged to be traversed opposite the winding-mandrel, means for connecting the thread-guide with 115 120 125 130

the cross-head, and means for uncoupling said connecting-means to arrest the operation of the guide.

12. In a winding machine, the combination with the rotating mandrel, of a continuously rotated disk-like cam, an oil-casting inclosing said cam and formed with parallel tracks on its upper edges, a cross-head slidable on said tracks, cleats over-
10 hanging the tracks to maintain the cross-head in place thereon, means on the cross-head engaging the cam to cause it to be reciprocated therefrom, a thread-guide adapted to be traversed in relation to the winding-
15 mandrel, and means for connecting said thread-guide to be reciprocated from the crosshead.

13. In a winding machine, the combination with a rotatable cop-holder, of a thread-
20 guide adapted to be traversed in relation thereto, a traverse-cam, a crosshead reciprocated from said cam, a rockable lever connected with the thread-guide, means for coupling the lever to the crosshead to cause it
25 to be oscillated therefrom to reciprocate the guide, and means for uncoupling the lever from the crosshead to arrest the operation of the guide.

14. In a winding machine, the combination with a rotatable cop-holder, of a thread-
30 guide adapted to be traversed in relation thereto, a traverse-cam, a crosshead reciprocated from said cam, a rockable lever connected with the thread-guide, means movable on said lever to engage the crosshead to adapt the lever to be oscillated thereby to reciprocate the guide, and means to disconnect the engaging-means to arrest the operation of the guide.

40 15. In a winding machine, the combination with a rotatable cop-holder, of a thread-guide reciprocable longitudinally thereof, a traverse-cam, a crosshead reciprocated from said cam, a pivoted lever connected with the guide, and means slidable on the lever to engage with the crosshead to cause the lever to be oscillated therefrom to reciprocate the guide.

16. In a winding machine, the combination with a rotatable cop-holder and a reciprocable thread-guide, of a lever connected to reciprocate the guide, a continuously reciprocated traverse-slide formed with a slot, and means on the lever engageable with
55 the slot to couple the lever with the slide to cause it to be oscillated therefrom.

17. In a winding machine, the combination with a rotatable cop-holder, of a reciprocable thread-guide, a reciprocating slide, means to reciprocate the slide, a lever oscillated from said slide and connected to reciprocate the thread-guide, connecting-means on the lever slidable into and out of engagement with the slide to control its oscillation therefrom, and means to disen-

gage the connecting-means from the slide to arrest the operation of the lever and the thread-guide reciprocated thereby.

18. In a winding machine, the combination with a rotatable cop-holder, of a reciprocable thread-guide, a reciprocating traverse-slide, means to reciprocate the slide, an extensible lever connected with the thread-guide, means on said lever engaging the slide to connect it to be oscillated therefrom, and means to extend the lever to release its engaging-means from the slide to arrest the reciprocation of the thread-guide.
70
75

19. In a traverse-motion for winding machines, the combination with a reciprocating traverse-slide, of a pivoted lever having an extension slidable in relation to its pivot, means on the extension engaging the traverse-slide to connect the lever to be oscillated therefrom, means to slide the extension to disengage its connecting-means from the slide and a thread-guide connected to the lever to be reciprocated therefrom during the oscillation thereof.
80
85

20. In a traverse-motion for winding machines, the combination with a reciprocating traverse-slide, of a pivoted lever adapted to be moved longitudinally in relation to its pivot, means on the lever engaging the slide to adapt it to be oscillated therefrom, a thread-guide connected to the lever to be traversed thereby, and means for moving the lever to release its engaging-means from the slide to arrest its oscillation and thereby
90
95
100

21. In a traverse-motion for winding machines, the combination with a reciprocating traverse-slide, of a lever pivoted on an axis at right-angles to the plane of movement of the slide and adapted to slide in relation to its pivot, a thread-guide connected to be reciprocated from the lever, connecting-means on said lever adapted to engage the slide, a spring for normally maintaining said connecting-means engaged with the slide, and means to slide the lever to disengage the connecting-means from the slide to arrest the operation of the thread-guide.
105
110

22. In a winding machine, the combination with a rotatable winding-mandrel, of an arm mounted for adjustment in relation to the axis of the mandrel and formed with a semi-cylindrical slot extending along its side, a thread-guide formed with an arcuate runner fitted to slide in the slot, a cleat on the arm having a semi-cylindrical bead fitted to the slot to retain the guide-runner therein, and means to reciprocate the guide in the slot while allowing it to pivot therein to adapt it to recede from the cop-holder
115
120
125
with the growth in the winding.

23. In a winding machine, the combination with the winding-mandrel, of a thread-guide adapted to be traversed longitudinally thereof, means to traverse the guide, a piv-
130

oted traverse-frame arranged to bear against the guide and to swing outward therewith with the growth in the winding, a pivoted weight-arm, and a link pivoted on the arm 5 in inclined relation thereto, said link pivotally connected with the traverse-frame to adapt it to act with a toggle-motion to push the weight-arm upwardly whereby its pressure on the traverse-frame is gradually 10 relieved as the link approaches a perpendicular relation thereto.

24. In a winding machine, the combination with the rotating cop-holder, of a traversing thread-guide, an oscillating lever 15 for traversing the guide, a reciprocating crosshead, means on the lever for engaging the crosshead to couple it thereto, and means normally out of range of movement of the lever but shiftable into the path thereof to 20 release its engaging-means from the crosshead to arrest the operation of the thread-guide.

25. In a winding machine, the combination with the rotating cop-holder, of a 25 thread-guide reciprocable in relation thereto, an oscillating lever connected to reciprocate the guide, a reciprocating crosshead, means 30 slidable on the lever to engage it with the crosshead to couple it thereto, and a bridge-member movable into the path of the lever and adapted to be engaged thereby to release its engaging-means from the crosshead.

26. In a winding machine, the combination with a rotating cop-holder, of a thread- 35 guide reciprocable in relation thereto, an oscillating lever for reciprocating the guide, a reciprocating crosshead, an extension slid- 40 able on the lever and carrying means for coupling it to the crosshead, and an arched bridge-piece movable into position to engage a projection on the lever whereby the latter riding over the bridge-piece will slide the lever-extension to uncouple it from the crosshead.

45 27. In a winding machine, the combination with a rotating cop-holder and a reciprocating thread-guide, of an oscillating lever for reciprocating the guide, a reciprocating crosshead, means slidable on the lever to

engage it with the crosshead, resilient means 50 for normally maintaining said slidable-means engaged with the crosshead, and means movable into the path of the lever to engage the sliding-means to disengage it from the crosshead and to hold the lever inoperative until released.

28. In a winding machine, the combination with a rotating winding-mandrel and a reciprocating thread-guide, of an oscillating lever connected to reciprocate the guide, 60 a reciprocating crosshead formed with a slot, means slidable on the lever to engage the slot in the crosshead and carrying a projection, and an arched bridge-piece adapted to be moved into the path of the 65 projection to cause it to ride thereover, said bridge-piece having a detent-depression with which said projection engages to hold the lever inoperative.

29. In a winding machine, the combination with a rotatable cop-holder, of driving-means therefor, a clutch for connecting the cop-holder with its driving-means, means to disconnect the clutch, a traversing thread-guide, an oscillating lever for reciprocating 75 the guide, a reciprocating crosshead for oscillating the lever, means for coupling the lever with the crosshead, and means for releasing said coupling-means and concurrently operating the clutch-shifting means. 80

30. In a winding machine, the combination with a rotatable cop-holder, of driving-means therefor, a clutch for connecting the cop-holder with its driving-means, a lever to shift the clutch to disconnect the cop-holder 85 from its driving-means, a traversing thread-guide, an oscillating traverse-lever for reciprocating the guide, a reciprocating crosshead for oscillating the traverse-lever, means to connect the traverse-lever with the crosshead, a stopping-lever for disconnecting the traverse-lever from the cross-head and for also operating the clutch-lever, detent-means 90 for maintaining said stopping-lever inoperative, and automatically-operated means for 95 releasing the detent-means.

In testimony whereof I affix my signature.

CHARLES D. REYNOLDS.
